[57] CLAIM

The ornamental design for a glassware rack, as shown
and described.

DESCRIPTION

FIG. 1 is a bottom, front and left side perspective view
of a glassware rack showing my new design, the broken
line disclosure of glassware and a portion of a shelf
being for illustrative purposes only and forming no part
of the claimed design;

FIG. 2 is a left side elevational view thereof, the undis-
closed right side being a mirror image of that shown;

FIG. 3 is a rear elevational view thereof; and

FIG. 4 is a top plan view thereof.
